UNITED STATES PATENT OFFICE.

WILLIAM L. LEE, OF PASS CHRISTIAN, MISSISSIPPI.

COMBINED RAKE AND HAY-FORK.

SPECIFICATION forming part of Letters Patent No. 667,536, dated February 5, 1901.

Application filed June 9, 1900. Serial No. 19,744. (No model.)

To all whom it may concern:

Be it known that I, WILLIAM L. LEE, a citizen of the United States, residing at Pass Christian, in the county of Harrison and State 5 of Mississippi, have invented certain new and useful Improvements in a Combined Rake and Hay-Fork, of which the following is a specification.

This invention relates to new and useful 10 improvements in combined rakes and hay-forks; and its primary object is to provide a device of simple and durable construction, the parts of which may be readily detached and replaced.

15 To these ends the invention consists in providing a head, to which are detachably secured a handle-socket and suitable braces therefor and having downwardly-extending teeth of ordinary construction. Forked tines 20 are inserted into the front face of the head and are provided with threads which engage with the head and retaining-nuts.

The invention also consists in the further 25 novel construction and combination of parts hereinafter more fully described and claimed, and illustrated in the accompanying drawings, showing the preferred form of my invention, and in which—

Figure 1 is a perspective view of the device. 30 Fig. 2 is a longitudinal section through the center thereof. Fig. 3 is a transverse section through the head, showing a tine in position therein.

Referring to said figures by numerals of 35 reference, 1 is a handle fitted with a suitable socket 2, which is threaded at its forward end and projects into and engages with an aperture 3, formed within a rake-head 4. A nut 5 engages the end of the socket to retain 40 the same in position, and braces 6 are bolted at opposite ends to the socket and head, respectively. Rake-teeth 7, of ordinary construction, project downward from the head 4

and are secured thereto in any suitable manner. Horizontally-extending threaded passages 8 are formed within the head, and each is adapted to be engaged by the threaded end of an upwardly-curved prong or tine 9, the end of which extends through the head and is provided with a locking-nut 10, as shown. 45 It is obvious that by this construction the device may be readily used for either of the purposes for which it is intended. In the event of injury or breakage of one of the prongs the same can be readily removed and 50 replaced.

In the foregoing description I have shown the preferred form of my invention; but I do not limit myself thereto, as I am aware that modifications may be made therein without departing from the spirit or sacrificing any 55 of the advantages thereof, and I therefore reserve the right to make all such changes as fairly fall within the scope of my invention.

Having thus fully described my invention, 60 what I claim as new, and desire to secure by Letters Patent, is—

The combination with a head having transverse threaded passages therein; of a threaded socket engaging the central passage, a handle detachably secured within said socket, braces secured to the socket at one end and detachably connected to the head at their opposite ends, rake-teeth secured to and extending downward from the head in a plane 70 at right angles to said handle, upwardly-curved tines, threaded ends thereto engaging the remaining passages within the head, and means for locking said tines in position.

In testimony whereof I affix my signature in presence of two witnesses.

WILLIAM L. LEE.
